CLAIM

The ornamental design for a wall-mounted, telephone
system unit, as shown.

DESCRIPTION

FIG. 1 is a front, right side perspective view from
below of a wall mountable speaker-receiver telephone
system showing my new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a left side elevational view thereof, the oppo-
site side being substantially a mirror image.

FIG. 1
